UNITED STATES PATENT OFFICE.

SAMPSON H. WEINHANDLER, OF NEW YORK, N. Y., AND JULIAN S. SIMSOHN, OF PHILADELPHIA, PENNSYLVANIA.

PROCESS OF ELIMINATING SALTS OF THE WEAK SULFUR ACIDS FROM FIXED PHOTOGRAPHIC MEDIA.

1,224,984.

Specification of Letters Patent.

Patented May 8, 1917.

Continuation of application Serial No. 22,352, filed April 19, 1915. This application filed September 9, 1916.
Serial No. 119,785.

To all whom it may concern:

Be it known that we, SAMPSON H. WEINHANDLER, a citizen of the United States, and a resident of the borough of Manhattan, city, county, and State of New York, and JULIAN S. SIMSOHN, a citizen of the United States, and a resident of the city of Philadelphia, in the county of Philadelphia and State of Pennsylvania, have invented certain new and useful Improvements in the Process of Eliminating Salts of the Weak Sulfur Acids from Fixed Photographic Media, of which the following is a specification.

15 This invention relates to photography, and more particularly to that part of the photographic art which pertains to the removal of chemicals of fixing baths used in photography, as for instance, the removal of sodium thiosulfate. Heretofore various methods of removing sodium thiosulfate, sodium sulfite and other salts of the weak sulfur acids have been used, but these methods have been found imperfect, due first to an 20 additional action of the added chemical on the image, and secondly, because of their comparatively high cost. For this reason, the washing method is still largely employed. This washing method frees the medium, as 25 the negative or positive, by washing it in running water or in fresh water from one-half an hour to an hour, such washing being necessary, as is well-known, because if the fixing chemicals are not removed, then the 30 plate, film or print would deteriorate in a short time and would not be fit for further use.

Our invention overcomes these disadvantages, and provides a method whereby photographic media, as plates, films or prints, 40 may be treated in a very efficient and time-saving manner, the use of our method requiring but a short time to insure the removal of the sodium thiosulfate, sodium sulfite, or other salts of the weak sulfur acids, 45 without injuring the photographic media treated.

In carrying out our invention, we develop the plate, film, or print in the usual manner 50 well-known in the art, and thereafter fix the plate, film or print with sodium thiosulfate, sodium sulfite or other salts of the weak sul-

fur acids, to which in some cases alum or citric acid or other suitable substance has been added, in the usual manner as well-known in the art. The plate, film or print, or other photographic medium, is then placed in an alkaline solution of sodium hypochlorite, this being made intentionally strongly alkaline, so that the alkalinity causes the pores of the gelatin on the film or plate to be opened, whereby the sodium hypochlorite can act upon the material desired to be removed, before the medium is bleached or otherwise injured. A suitable solution is 65 of such alkalinity that it requires 20 cc. of a 10% normal solution of sulfuric acid to neutralize 1 cc. of it. It is necessary to open the pores of the gelatin very rapidly, as before set forth, in order 70 to remove the "hypo" for the sodium hypochlorite bleaches the film, which is objectionable. A solution of the strength before described can accomplish the desired result in three minutes, in which time there is no 75 bleaching of the films.

A suitable solution and a suitable relative concentration of the "OH" ions of the alkali with respect to the active ions of the sodium hypochlorite is obtained in a solution in 80 which seven ounces of soda ash are thoroughly intermixed with forty-five ounces of hot water, this solution being mixed with a second solution of two ounces of commercial bleach powder and thirty ounces of water. 85 Conditions, of course, will vary with the character of the film, the degree of acidity of the hypo bath, etc., but from two to three minutes are sufficient.

By means of the addition of the sodium carbonate to the bleach powder, sodium hypochlorite and an insoluble calcium carbonate are formed, which latter substance can be removed in any suitable way. The sodium hypochlorite thus produced is intentionally 95 strongly alkaline, due to the formation of some sodium hydrate. This sodium hydrate is formed because commercial bleach powder contains calcium oxid, which when acted upon by sodium carbonate, produces sodium 100 hydrate.

The resulting reaction produces a soluble substance (Glauber salt or sodium sulfate), which is readily soluble and quickly removed.

by dipping or washing in water. At the same time, the alkalinity has a favorable action upon the photographic medium, in that it prevents it from becoming brittle.

5 A photographic medium treated by our improved process in the manner before described, when placed in an aqueous solution of potassium permanganate and sodium hydrate does not change the pink color thereof, whereas if any such media are not sufficiently treated, so that traces of the salt of the weak sulfur acid remain, then the pink coloring is changed to a brownish-yellow color.

10 Our process adapts itself especially to the treatment of the ordinary films for motion pictures, and for photographic processes where rapidity of manipulation is essential. A large amount of time is saved, and also a considerable expenditure due to the need 20 of large quantities of water.

15 A second feature of our invention consists in producing sodium hypochlorite simultaneously with the immersion of the films, plates, or other media, after they have 25 been treated with the sodium thiosulfate, sodium sulfite, or other salts of the weak sulfur acids. For this purpose, the plate, film, print or other medium is placed in a container of suitable proportions, in which 30 non-attackable suitably spaced electrodes are placed, and in which an aqueous solution of ordinary salt (sodium chlorid) is placed.

20 An apparatus suitable for carrying out this part of our invention is shown in the drawing, in which 1 represents an ordinary tank for electrolysis, containing the solution 35 2, this tank having the electrodes 3 and 4. Current can be admitted by means of the switch 5 which makes contact with the 40 mains 6 and 7. A resistance 8 is provided, as also an ammeter A and a voltmeter B. More solution can be admitted from an upper tank 18 and a pipe 9 having the valve 10. By the electrolysis produced by the 45 passage of the electric current, sodium hypochlorite can be produced, the amount thereof depending upon the current, which can be regulated so as to produce just such a quantity of sodium hypochlorite as is necessary 50 to combine with the sodium thiosulfate or the like, and form the soluble sodium sulfate. The strong alkalinity of the solution will at the same time give the advantages before described, to wit, the rapid opening 55 of the pores of the gelatin of the photographic medium. In the formation of sodium hypochlorite as described, by electrolysis, a small amount of chlorin escapes as the gas is formed, leaving an excess of sodium hydrate (NaOH), thus producing the 60 alkalinity of the solution, this being due to the fact that there is only a reasonable mixing of the products from the anode or cathode. This is different from the known 65 process of making sodium hypochlorite, in

which large quantities are produced with constant agitation, whereas in our process no agitation is allowed to take place.

70 After the photographic medium has been subjected to the action of the sodium hypochlorite, it is removed to a water bath, water spraying device, or other suitable means for the purpose of washing out of the solution the sodium sulfate. This washing only takes a few minutes, as dipping in water for sixty to one hundred and twenty seconds, whereby the complete removal of the sodium thiosulfate or the like is assured.

75 Gelatin has been spoken of, but it is clear that the invention can be applied to other media usable in the photographic arts and processes. Similarly, instead of sodium hypochlorite, we have found that sodium hypobromite, which can also be obtained by the electrolysis of sodium bromid, may be 80 used, and we have found further that any electrolysis carried out as above described, using an aqueous solution or one of an alkali, produces the desired result.

85 Similarly, the alkali and the sodium hypochlorite need not be combined in one solution as is obvious, since the medium can be immersed in an alkaline solution having the desired degree of alkalinity until the pores of the gelatin are thoroughly opened, and it 90 can then be immersed into a solution of the sodium hypochlorite.

95 We have described an effective embodiment of our invention, but it is clear that numerous changes may be made in the details thereof, such as in the strength and proportions of solutions and the like, to 100 meet various conditions, and we do not wish to be limited thereto.

105 We claim:—

1. The process herein described of treating a photographic medium, which consists in subjecting the thiosulfate held in the gelatin of the films, to the action of a strongly alkaline solution of sodium hypochlorite for 110 producing a soluble substance, said solution being sufficiently alkaline to rapidly open the pores of said gelatin before said film is bleached, and washing out this soluble substance.

115 2. The process herein described of treating developed and fixed photographic medium containing salts of the weak sulfur acids, which consists in subjecting said medium to the action of a strongly alkaline 120 solution of sodium hypochlorite for the purpose of opening the pores of the gelatin rapidly, said solution of sodium hypochlorite forming a soluble substance of said salts, and then removing said soluble substance, said 125 alkaline solution being so strongly alkaline as to open the pores of the gelatin before said film is bleached.

3. The herein described process of treating a developed and fixed photographic 130

- medium containing a salt of weak sulfur acids to a solution of a halogen salt, which is being subjected to the action of a controlled electric current, whereby the salt of 5 a hypo halogen acid is produced in a quantity proportional to the quantity of said weak sulfur acid and said medium, for forming a soluble substance therewith, and thereafter removing said soluble substance, said 10 solution being maintained in a state of substantial quiescence, an alkaline hydrate being formed by the action of said electric current, so as to make said solution strongly alkaline as to open the pores of said gelatin, 15 before said medium is bleached.
4. The herein described process of treating fixed and developed photographic media containing salts of the weak sulfur acids, which consists in subjecting them to the action of 20 an aqueous solution of common salt which is being decomposed by a controlled electric current, to produce quantities of sodium hypochlorite for forming a soluble substance with the said salt of the weak sulfur acid, 25 washing out said soluble substance with
- water, said solution being maintained substantially quiescent during the electrolysis, and being always maintained so strongly alkaline as to rapidly open the pores of the gelatin of said medium, before said medium 30 is bleached.
5. The process herein described of treating fixed and developed photographic medium containing a salt of the weak sulfur acids, which consists in treating said medium with 35 a strongly alkaline solution of salt of a hypo halogen acid for producing a soluble substance, and washing out said soluble substance, said solution being so strongly alkaline as to produce the said soluble substance 40 before said film is bleached.

In testimony, that we claim the foregoing as our invention, we have signed our names in presence of two subscribing witnesses.

SAMPSON H. WEINHANDLER.
JULIAN S. SIMSOHN.
